GRINDING MACHINE

William J. Bryant, Springfield, Vt., assignor to
 Bryant Chucking Grinder Company, Springfield,
 Vt., a corporation of Vermont

Application July 1, 1943, Serial No. 493,032

6 Claims. (Cl. 51—105)

In grinding work to a desired contour, it is well known that by relatively feeding a contoured grinding wheel directly and without any lateral component, sometimes termed a "plunge" or "form" grind, a better finish may be obtained than when the desired contour is generated by a wheel having a traversing motion as well as a feeding motion. The raceways for ball bearings, for example, should have a high finish, and hence form grinding, at least for the final finishing grinding, is preferable to generating grinding. Where there is room to oscillate the grinding wheel, the grinding operation of such raceways has often been divided into two stages, the first of which comprises the roughing cut, accomplished by generation in one machine, followed by a finish forming grinding done in another machine. This, however, requires re-chucking of the work when changing from one machine to the other, and this necessitates that considerable stock be left for removal in the finishing grinding to allow for unavoidable inaccuracies in the re-chucking, and a finishing wheel best suitable for finishing is not well adapted to rapid removal of stock. To avoid this, it has also been proposed to rough and finish grind by the same wheel, the rough grinding being accomplished by generation and while using coolant, and the finishing grinding while the wheel oscillating means used during rough grinding is clamped, and by a forming cut without coolant. By cutting dry during the finishing forming cut, the action is softer than during the wet roughing cut. Even with this change of conditions, however, the use of the same wheel for both roughing and finishing cuts does not give the best results, as a grinding wheel most suitable for one of these operations is not the best suited for the other.

One object of the present invention, therefore, is to provide a grinding machine with both rough grinding and finish grinding wheels, the machine being so constructed that the particular wheel desired may be presented to the work in proper grinding relation thereto, and without re-chucking and in which the change from one to the other wheel may be effected easily and quickly.

A further object of the invention is to provide a machine in which wheels may operate as forming wheels, this adapting the machine particularly well to the exacting requirements of cutting ball bearing raceways.

A further object of this invention is to provide means by which that grinding wheel which is in

operation may be trued during the time that the other wheel is in operation.

To these ends, as well as others which may appear, in accordance with this invention, the two grinding wheels, one for rough grinding and the other for finish grinding, are secured to opposite ends of the same spindle which is so mounted that it may be turned end for end to present either selected wheel to the work.

10 Still another object of the invention is to provide a spindle, mounting such that when the spindle is turned end for end, it is also in such position that the grinding wheels clear the truing device so that it is not necessary to move the truing device out of operative position when reversal of the spindle is to be effected.

For a more complete understanding of this invention, together with further objects and advantageous constructions, reference may be had to the accompanying drawings in which

Figure 1 is a top plan view, somewhat diagrammatic, of a grinding machine embodying this invention.

Figure 2 is a fragmentary front elevation of the same.

Figure 3 is a detail sectional view to a larger scale on line 3—3 of Figure 1.

Figure 4 is a detail sectional view to the scale of Figure 3 on line 4—4 of Figure 2.

30 Figure 5 is a view similar to Figure 4, but showing the parts in different positions.

Figure 6 is a detail sectional view on line 6—6 of Figure 3.

Figures 7 and 8 are detail sectional views on lines 7—7 and 8—8, respectively, of Figure 2.

Referring first to Figures 1, 2, 7 and 8, at 1 is indicated a bed of the grinding machine which is provided adjacent to its front and back edges with a pair of circular guide bars 2 secured thereto as by screws 2a. On these guide bars is slidably mounted a carriage 3 shown as provided with bearing shoes 4 slidably supported on the bars 2. This carriage 3 supports a cross slide 5 upon which is mounted a suitable work support

40 6. As shown this work support carries a rotary work spindle 7 having on its outer end a pulley 8 by which it may be rotated and on its inner end, a work-holding chuck of any suitable description at 9.

45 6. Means may be provided for feeding the cross slide back and forth in the well known manner and to this end, a feed wheel 10 has been illustrated, this being connected to turn a splined shaft 90 slidably mounted within a feed screw 91 having threaded connection with the cross slide 5.

50 Means may be provided for feeding the cross slide back and forth in the well known manner and to this end, a feed wheel 10 has been illustrated, this being connected to turn a splined shaft 90 slidably mounted within a feed screw 91 having threaded connection with the cross slide 5.

This cross slide is held with an abutment member 92 in contact with a former cam 93 carried by the carriage 3 by means of a weight 94 connected to the cross slide 5 through a flexible connector 95 passing about a pulley 96, as shown in Figure 8. The former cam 93 may be moved on the carriage 3 relative to the cross slide 5 by means of hydraulic cylinder 97 to thus effect a transverse feeding of the work towards the grinding wheel periphery.

The slide 3 may be caused to move axially along the guide bars 2 by any suitable means, but as herein shown the means is hydraulic, comprising a hydraulic cylinder 10 containing a movable piston 11 connected through a piston rod 12 to the carriage 3. Pipes 13 and 14 communicating with opposite ends of the cylinder 10 beyond the piston 11 are shown for the purpose of controlling the supply and discharge of fluid under pressure to cause the desired axial motion of the carriage 5. The former cam 93 as shown best in Figure 1 is tapered and may be moved axially to cause feed and retracting motion of the cross slide 5 as by a hydraulic pressure cylinder 97 having a piston 98 connected to the former cam.

Likewise carried by the bed 1 is a support 15, this being shown in Figure 7 as fixed to the bed 1 as by ears 16 integral with the support 15 bolted to inwardly directed flanges 17 on the bed 1. This support 15, as shown best in Figures 3 to 5, is provided with an upright cylindrical portion 20 within which is slidably mounted a sleeve portion 21 depending from a grinding wheel turret 22. As shown the portion 21 is integral with the turret. This turret 22 has an integral upstanding side piece 23 for engagement with the base 24 of a grinding wheel spindle carrier 25, and this carrier 25 may be held against the undercut surface of the portion 23 by means of a member 26 having a beveled edge 27 mating the beveled edge 28 on the wheel carrier 25. This member 26 may be secured to the turret 22 by means of screws 30, thus to clamp the spindle carrier 25 in position thereon.

The spindle carrier 25 has journaled therein the grinding wheel spindle 35 having a pair of grinding wheels 36, 36a, one secured at each end thereof. The spindle support 25 may be provided with any suitable means for rotating the spindle 35. For example, it may comprise the stator of a motor of which a portion of the spindle 35 forms the rotor.

The turret 22 is permitted an axial up and down motion by reason of the slidable mounting of the sleeve 21 in the support 15, and when it is at its upper limit of motion, it is also permitted a rocking motion through substantially a 180° angle so as to permit end to end reversal of the spindle 35, thus to present either selected of the wheels 36 and 36a toward the work carried by the work holder 9. One of the wheels 36a may be especially suitable for rough grinding and the other 36 especially suitable for finish grinding. When the turret is in its downward position, it is in proper relation for a grinding operation on the work, and means are therefore provided for locking the turret against rotation when it is in this downward position. To this end, opposite sides of the base portion of the turret 22 are shown as beveled as at 40 and these beveled portions, when the turret is in its lowered position, as shown in Figure 4, engage oppositely beveled surfaces 41 of a pair of locating and locking strips 42. These strips 42 are secured as by screws 43 to the upper face of the support 20 and in order that they

may be accurately aligned, adjusting screws 45 threaded through bars 46 permanently secured to the upper face of the support 20, engage the strips 42 adjacent to opposite end portion thereof.

5 When the turret is lifted into the position shown in Figure 5, it is freed from the locating strips 42 and is then in position to be turned so as to present the desired wheel 36 or 36a toward the work. The lifting of the turret is shown as 10 produced by fluid pressure. To this end, the sleeve portion 21 has extended thereinto a hollow rod 45, the upper end of which is provided with a piston 46 which bears against the inner wall of the sleeve to form a pressure chamber between it and the upper end of the sleeve, into which fluid under pressure may be passed or from which fluid pressure may be discharged through a pipe 47 secured to the lower end of the rod 45. As 15 shown this rod 45 has a head 48 at its lower end engaged by a cover plate 49 closing off the lower end of a cylindrical portion 50 of the support 20, and the rod 45 has a lower reduced diameter end portion threaded for the reception of a nut 51 engaging a washer 52 which bears against the 20 lower face of the cover plate 49. The turret is 25 normally pressed downwardly into locating engagement with the strips 42, not only by its own weight, but as shown, by a coil spring 55 reacting between the lower face of the piston 46 and the top face of a washer 56 interposed between it and an annular plate 57 secured to the lower end of the sleeve 21.

Intermediate to the end portions of the sleeve 21 it is provided with a portion 60 of circular periphery provided with gear teeth 61 forming a partial pinion with which mesh teeth 62 on a cylindrical rack bar 63 mounted for axial motion in a bore 64 in the support 15. This rack bar 63 is in the form of a piston rod having a piston 69 (see Figures 3 and 6) riding in a cylindrical bore 65 of the support 15, which bore forms a hydraulic cylinder closed off at its outer end by a cylinder head 66. By motion back and forth of the piston 64 and the rod 63, it will be evident 40 that the sleeve 60, together with the turret carrying the wheel spindle, may be rocked through 180° in one or the other direction thus to reverse the spindle 35 end for end to present either selected of the two wheels into operative relation 45 to the work. In order to accurately define the limits of this turning motion, adjustable screw stops 67 and 68 may be employed, the stop 67 extending through a plate 70 closing off the inner end of the bore 64 within which the piston rod 63 is movable, and the stop 68 being carried 50 by the cylinder head 66. Suitable pressure and discharge pipe connections at 72 and 73 permit the admission and discharge of fluid under pressure from opposite sides of the piston 64 as desired in order to move the rack bar 63 in the desired direction.

The arrangement of the two wheels on opposite ends of the spindle also makes feasible the truing of that wheel out of operative relation to the work 55 while the other wheel is operating on the work, so that no time is lost from grinding due to truing, and the lifting of the spindle from grinding position before it is reversed end for end may be utilized to clear the wheels from the truing mechanism, so that it is unnecessary to retract the truing mechanism from truing position to permit such reversal to be effected. This is shown best 60 in Figures 1, 2 and 7. The truing device 80 shown in these figures is supported by a post 81 rising 65 from a turntable 82 journaled on an upright pivot 70

bolt 83, and supported through a thrust ball bearing 84 from a cross feed slide 85 carried by a longitudinal slide 86, mounted on a portion 87 projecting upwardly from the wheel support 16. Any suitable means such as is well known in the art may be provided for adjusting the slides 85 and 86 so as to present the truing tool at the proper position to true the wheel which is on that end of the spindle remote from the work at any particular time. As shown such adjusting means may be actuated by turning the vernier knobs 88 and 89, respectively. As shown the truing device is arranged to true the wheel edge to convex contour as by rocking the turntable, which may be done by moving the turret handle 90 between the two dotted line positions shown in Figure 1. Such a wheel edge contour is useful, for example, in grinding the raceways for ball bearings.

From an inspection of Figure 7, also, it will be seen that when the spindle carrier 25 is lifted to its upper position, shown in broken lines, ready to be turned to reverse the spindle end for end, the trued grinding wheels are in the dotted line position of Figure 7 where they clear the truing device so that removal or retraction of the truing or dressing mechanism is not required to permit this change of grinding wheels by reversing the spindle end for end.

In operation the work carriage being retracted and with the roughing wheel extending toward the work support 6, the slide 5 being retracted and a work piece to be ground being in position in the work support, the work carriage 3 is advanced toward the wheel by motion of the piston 11 until the roughing wheel 36a is in proper axial relation thereto. While the wheel is being rotated the work slide 5 is fed by axial motion of the former cam 93 relative to the cross slide 5 on the carriage 3, which is moved by the piston and hydraulic cylinder 91 carried by the work carriage 3 to effect a rough forming cut.

When the work has been ground to the desired depth, during which time the finishing grinding wheel 36 may be trued by the truing device actuated by moving the handle 90, the work cross slide 5 is backed off by reverse motion of the former cam 93, after which the work carriage 3 is retracted and the wheel spindle turned end for end to present the finish grinding wheel 36 toward the work. The work carriage 3 is thereupon moved axially of the work to bring the work opposite to the finish grinding wheel 36, after which by moving the former cam, the cross slide 5 is moved to feed the work to the finish grinding wheel. After sufficient finish form grinding and during which the rough grinding wheel may be trued, the cross slide 5 is again retracted to clear the wheel, after which the slide 3 is retracted and the finished work piece removed and replaced by an unground piece ready for the start of the next cycle with the spindle reversed end for end to present the rough grinding wheel 36a for the first grinding action on the work piece.

From the foregoing description of an embodiment of this invention, it should be evident to those skilled in the art that various changes and modifications might be made without departing from the spirit or scope of this invention.

I claim:

1. A grinding machine comprising a bed, a work holder carried by said bed, a support carried by said bed, a turret pivotally carried by said support and mounted for motion axially of said pivot, elements on said support and turret cooperating when said turret is in operative axial position to

hold said turret in either of two angular positions, in one of which one of said wheels is presented toward said work holder and in the other of which the other of said wheels is presented toward said work holder, means for moving said turret axially into and out of said one position, means effective when said turret is out of said axial position to rotate said turret from one to the other of said angular positions, and means for relatively moving said work holder and spindle to present a grinding wheel turned toward the work holder into operative relation to work held by said holder.

2. A grinding machine comprising a bed, a work holder carried by said bed, a support carried by said bed, a sleeve journaled in said support and axially movable therein, a turret carried by said sleeve, a hollow rod fixed to said support and projecting axially into said sleeve, a piston carried by said rod riding within said sleeve, a spring surrounding said rod and reacting between a portion of said support and said piston and normally holding said turret in one axial position, means holding said turret in either of two angular positions when in the axial position to which it is urged by said spring, a rotary grinding wheel spindle carried by said turret, a grinding wheel on each end of said spindle, one of said wheels being presented toward the work when said turret is in one of said angular positions and the other of said wheels being presented toward the work when said turret is in the other of said angular positions, said sleeve having teeth cut into its periphery, a rack bar mounted for axial motion in said support and engaging said teeth, means for moving said rack bar axially when said turret is moved from said held position to thereby turn said turret to change from one to the other of said grinding wheels presented toward the work, and means for moving said work holder and support relatively to cause the wheel so presented to operate on work carried by said work holder or to be retracted therefrom.

3. A grinding machine comprising a bed, a work holder carried by said bed, a support carried by said bed, a turret on said support mounted for raising and lowering and for rocking motion, said turret having oppositely disposed beveled surfaces, locating bars carried by said support and provided with oppositely beveled surfaces for cooperation with the beveled surfaces of said turret when said turret is in its lowered position to hold said turret in either selected of two angular positions, a rotary spindle carried by said turret, a grinding wheel on each end of said spindle, one of said grinding wheels being presented toward said work holder when said turret is in one of said angular positions and the other of said grinding wheels being presented toward the work when said turret is in the other of said angular positions, means for lifting said turret out of its lowered position into a position in which it is free to be turned from one to the other of said angular positions, means for turning said turret from one to the other of said angular positions when said turret is in lifted position, and means for relatively moving said work holder and turret when said turret is in lowered position to cause the grinding wheel presented toward said work holder to grind work held by said work holder.

4. A grinding machine comprising a bed, a rotary work holding chuck carried by said bed, grinding mechanism including a rotary spindle also carried by said bed, a grinding wheel on each end of said spindle, means supporting said spindle for reversal end for end to selectively present

either selected of said wheels into operative relation to work carried by said chuck, whereby said wheels may be presented successively to the work piece while said work piece remains chucked, a tapered former cam arranged lengthwise of the axis of rotation of said chuck, means for moving said cam lengthwise, and operative connections between said cam and chuck causing said movement of said former cam to move said chuck transverse to its axis to effect feed and retraction between that wheel in operating position at any one time and work carried by said chuck.

5. A grinding machine comprising a bed, a grinding mechanism including a rotary spindle carried by said bed, a grinding wheel on each end of said spindle, means for moving said spindle transverse to its axis from and to a definite transverse position, means effective only when said spindle is out of said definite position for turning said spindle end for end, and a wheel 15 truing mechanism in operative relation to which either of said wheels may be presented by the turning of said spindle end for end and when said

spindle is in said definite position, said spindle when out of said position being cleared from said device for such end for end turning by the transverse motion of said spindle away from said definite position.

10 6. A grinding machine comprising a bed, a turret pivotally and axially movable with respect to said bed, a grinding wheel spindle carried by said turret and extending transverse to the pivotal axis of said turret, means holding the said turret against turning and in either of two angular positions with said spindle in reversed end to end relation when said spindle is in one axial position, said turret being free to be turned when said turret is in another axial position, and a wheel truing device carried by said bed in position to true one or the other of said wheels when said turret is in said one axial position depending upon the 15 end for end position of said spindle, said turret when in said other axial position holding said wheels in cleared relation to said truing device for end to end reversal of said spindle.

20 WILLIAM J. BRYANT.
